OIL-CLOTH-PRINTING MACHINE.

No. 801,819.

Specification of Letters Patent.

Patented Oct. 10, 1905.

Original application filed December 8, 1904, Serial No. 236,011. Divided and this application filed March 11, 1905. Serial No. 249,659.

To all whom it may concern:

Be it known that I, WILLIAM HUBELI WALDRON, a citizen of the United States, and a resident of New Brunswick, in the county of 5 Middlesex and State of New Jersey, have invented a new and Improved Oil-Cloth-Printing Machine, of which the following is a full, clear, and exact description, this being a division of the application for Letters Patent of 10 the United States, Serial No. 236,011, filed by me on December 8, 1904.

The invention relates to machines for imprinting designs in various colors upon oil-cloths and other fabrics by the use of intermittently-reciprocating printing-blocks; and the object of the invention is to provide a new and improved machine for printing oil-cloth arranged to insure a positive locking of the intermittent driving mechanism for the color- 20 trough, to cause an easy driving and locking of the said mechanism without shock or jar, to allow convenient adjustment or detachment of the printing-blocks, and to reduce the weight of the color-trough to a minimum.

25 The invention consists of novel features and parts and combinations of the same, as will be more fully described hereinafter and then pointed out in the claims.

A practical embodiment of the invention is 30 represented in the accompanying drawings, forming a part of this specification, in which similar characters of reference indicate corresponding parts in all the views.

Figure 1 is a side elevation of the improvement. Fig. 2 is an enlarged cross-section of the same on the line 2 2 of Fig. 1. Fig. 3 is an enlarged plan view of part of one of the printing-blocks and its support, and Fig. 4 is an enlarged longitudinal sectional elevation 40 of one of the color-troughs.

On the main frame A of the oil-cloth-printing machine is held a table B, over which is intermittently moved the oil-cloth or other fabric C to be printed by the use of a series 45 of printing-blocks D, (one only being shown in the drawings,) reciprocating intermittently in a vertical direction and supplied with color by printing-rolls E, mounted to turn in color-troughs F, adapted to travel intermittently 50 forward and backward on the frame A at the time the printing-blocks are in a raised resting position, so that the printing-rolls E ink the faces of the said blocks, the several color-

troughs being linked together in the usual manner to move in unison. 55

The several devices of the machine so far described are those of the ordinary oil-cloth-printing machines now generally in use.

The color-troughs are usually very heavy, and it requires considerable force to properly 60 start the troughs on their travel, and when the machine is in operation the momentum acquired by the color-troughs in their rapid forward-and-backward motion tends to carry the moving parts beyond their proper positions. In order to insure an easy starting and accurate stopping and locking of the color-troughs and to reduce their weight, the following arrangement is had: On one end of the main frame A is journaled a transversely-extending main shaft G, provided with a suitable clutch-pulley G', connected by belt with other machinery for imparting a continuous rotary motion to the main shaft G. On the latter is secured a pinion G² in mesh with an 70 intermediate gear-wheel G³, secured on a shaft G⁴, journaled on the main frame A and carrying a pinion G⁵ in mesh with a gear-wheel G⁶, secured on a shaft H, journaled in suitable 75 bearings on the main frame A and carrying on each end a mutilated gear-wheel I, adapted to mesh with a mutilated gear-wheel I', secured on a crank-shaft I², journaled in suitable 80 bearings on the main frame A. On each end of the crank-shaft I² is secured a counterbalanced crank-arm J, connected by a link J' with a rocking lever J², fulcrumed at its lower end on the main frame A and connected at its upper free end by a link J³ with the first color-trough F, connected by a link J⁴ with the next 90 color-trough, it being understood that the several color-troughs of the series are connected with each other by links J⁴, so that all the color-troughs move in unison.

The mutilated gear-wheel I is provided with 95 a smooth segmental rim portion I³, adapted to fit alternately onto smooth concave rim portions I⁴ and I⁵, formed on the mutilated gear-wheel I' between the two sets of teeth thereof, as plainly illustrated in Fig. 1. Now when 100 the segmental rim portion I³ is in mesh with the concave rim portion I⁴ or I⁵ then the mutilated gear-wheel I' is held against rotation—that is, the said portions I⁴ and I⁵ form a Geneva stop to allow rotation of the mutilated 105 gear-wheel I and its portion I³ without revolv-

ing the mutilated gear-wheel I' until the teeth of the mutilated gear-wheel I move in mesh with the corresponding set of teeth on the mutilated gear-wheel I' . In order to turn the mutilated gear-wheel I' sufficiently to bring this corresponding set of teeth in mesh with the mutilated gear-wheel I , a friction-roller I^6 is journaled on the mutilated gear-wheel I , and this friction-roller is adapted to engage a projection or tooth I^7 or I^8 , held on the smooth rim portion I^4 or I^5 of the mutilated gear-wheel I' .

When the machine is in operation, the rotary motion of the shaft G is transmitted to the shaft H by the gearing described, and the rotary motion of the shaft H causes the mutilated gear-wheel I to rotate in the direction of the arrow a' , (see Fig. 1,) so that the friction-roller I^6 finally moves in contact with the lug I^7 , thus turning the mutilated gear-wheel I' a sufficient distance to bring the teeth of the mutilated gear-wheel I' in mesh with the teeth of the revolving mutilated gear-wheel I . When this takes place, a rotary motion is given to the mutilated gear-wheel I' and its shaft I^2 in the direction of the arrow b' , so that the crank-arms J impart a rocking motion to the levers J^2 to move the color-troughs F from the left to the right under the corresponding printing-blocks D , so that the ink-rolls E ink the printing-faces of the said printing-blocks D . When the troughs F have passed the printing-blocks D , then the teeth of the mutilated gear-wheels I and I' move out of mesh with each other and the smooth rim portion I^5 is moved in engagement with the smooth segmental rim portion I^3 , so that the mutilated gear-wheel I' is held against further rotation for the time being—that is, until the friction-roller I^6 comes in contact with the projection or tooth I^8 to move the mutilated gear-wheel I' again in mesh with the mutilated gear-wheel I . When this takes place, the mutilated gear-wheel I' is again rotated, and with it the shaft I^2 , so that the crank-arms J are actuated to impart a return traveling motion to the color-troughs F by the link-and-lever connection above described, it being understood that during the time the color-troughs F were at rest in their right-hand side positions the printing-blocks D descended, made an impression, and returned to their uppermost positions previous to the return movement of the color-troughs F . The fabric C to be printed is attached at its side edges to pins K' , projecting from endless belts or aprons K , provided at their under sides with spaced lugs K^2 , traveling in suitable longitudinally-extending guideways A' , formed on the main frame A , as plainly indicated in Fig. 2. The lugs K^2 are adapted to engage notches K^3 , formed in the peripheral faces of drums K^4 , secured on a shaft L , journaled in suitable bearings on the end of the main frame A , the said shaft L carrying star-

wheels L' , having radial slots L^2 , adapted to be engaged successively by friction-rollers L^3 and L^4 , journaled on cam-wheels L^5 , secured on a shaft L^6 , mounted to turn in suitable bearings on the main frame A . The shaft L^6 is continually rotated from the shaft H , and for this purpose the latter is provided with a gear-wheel H' in mesh with a gear-wheel H^2 , secured on the shaft L^6 . When the machine is in operation and the shaft L^6 is rotated, then the friction-rollers L^3 L^4 are alternately moved in mesh with successive radial slots L^2 to impart an intermittent rotary motion to the star-wheels L' , the shaft L , and the drums K^4 , secured thereon, to impart an intermittent traveling motion to the aprons K and the fabric C temporarily attached thereto. The travel given to the fabric C corresponds to the width of a printing-block D , and the arrangement is such that the movement of the fabric C takes place at the time the printing-blocks D are moving vertically, the fabric being at rest during the time the impressions are made.

Each printing-block D is removably supported by a frame N , mounted to slide with its side arms N' vertically in suitable guideways A^2 , attached to the sides of the main frame A , and the lower ends of the side arms N' of the frame N are provided with friction-rollers N^2 , traveling on the peripheral faces of cam-wheels O , secured on a transversely-extending shaft O' , provided with a gear-wheel O^2 in mesh with a pinion O^3 , secured on a shaft O^4 , journaled on the main frame A and provided with a gear-wheel O^5 in mesh with the pinion G^2 on the main driving-shaft G . The first shaft O' (shown in Fig. 1) is provided with the usual crank-arm O^6 , connected by a link O^7 with a similar crank-arm on the next following shaft O' , carrying similar mechanism to the one described for raising and lowering the frame N and the printing-block D . In other words, the several raising and lowering devices for the printing-blocks D in the series are connected together, so that the several printing-blocks D are operated in unison.

In order to quickly attach or detach the printing-blocks D to or from their frames N and to adjust the said printing-blocks to bring the same in proper position to insure an accurate impression, the following device is provided, special reference being had to Fig. 3.

The frame N for supporting a printing-block D consists, essentially, of transversely-extending beams N^0 , preferably in the form of channel-irons, bolted or otherwise secured at their ends to arms N^4 , resting on the upper surfaces of heads N^5 , formed on the upper ends of the side arms N' , each arm N^4 being engaged by a vertically-disposed bolt P , extending through an enlarged opening N^6 , formed in the arm N^4 and the bolt screwing in the corresponding head N^5 . By loosening

the bolt P the beams N³, with their heads N⁵, can be shifted transversely, and when the desired adjustment has been reached the bolts P are screwed up to securely fasten the arms N⁴ to the heads N⁵ of the side arms N'. Each bolt P is provided with a suitable washer P' to cover the enlarged opening N⁶ in the corresponding arm N⁴. Minute transverse adjustment of the arm N⁴ and beams N³ is had when the bolt P is loosened by a suitable screw P², screwing in the outer end of the head N⁵ against the outer end of the corresponding arm N⁴. A longitudinal adjustment is given to the beams N³ and their arms N⁴ by the use of a block P³, fitting against the inner face of the head N⁵ and provided with a pin P⁴, extending into an elongated slot N⁷, formed in the arm N⁴. Screws P⁵, screwing in the head N⁵, engage the ends of the block P³ to adjust the same longitudinally, it being understood that the corresponding pin P⁴, moving with its block P³, shifts the arm N⁴ in a like direction until the desired position is reached.

From the foregoing it will be seen that the supporting-beams N³ for the printing-blocks D can be adjusted longitudinally and transversely on the head N⁵ of each side arm N' to bring the block D in proper alignment relative to the fabric to be printed.

In order to attach each block D to the beams N³, a number of plates D' are secured to the upper face of the block D, and on the side of each plate D' is held a clamping-arm D², engaged by a bolt D³, screwing in the plate D', the clamping-arm abutting with its outer end on the plate D' and its inner end on the lower flange of the corresponding beam N³. A set-screw D⁵ screws in a lug D⁴ on each side of the plate D', and this set-screw abuts against the outer edge of the lower flange of the corresponding beam N³, so that when the bolts D³ are loosened on both sides of each plate D' then a longitudinal adjustment can be had by screwing up and unscrewing the set-screws D⁵ correspondingly. After the desired adjustment is had the bolts D³ are screwed up tightly to securely clamp the upper faces of the plates D' to the under faces of the transverse beams N³.

In order to reduce the weight of the color-troughs F to a minimum, each of the said color-troughs is provided with wheeled side frames F', connected with each other by a connecting-plate F², forming a support for a box F³, preferably made of light sheet metal and containing the desired color. It is understood that heretofore the color-box formed an integral part of the wheeled frame and had to be made very heavy, owing to the great width of the machine, but by using light wheeled frames connected with each other and a separate light color-box it is evident that the color-trough is materially reduced in weight. The printing-roll E extends into

the color contained in the color-box F³, and the side frames F' of the color-trough support the usual adjustable doctors Q.

The gearing for rotating the inking-roll E during the forward and backward travel of the color-trough is of usual construction, so that further detailed description of the same is not deemed necessary.

Having thus described my invention, I claim as new and desire to secure by Letters Patent—

1. An oil-cloth-printing machine provided with an intermittent driving-gear for the fabric to be printed, comprising a drum, over which passes the fabric - carrying aprons, a star-wheel revolving with the drum and having radial slots, and a shaft having oppositely-disposed arms and friction-rollers on the arms adapted to pass alternately into the said slots to intermittently rotate the drum. 80

2. An oil-cloth-printing machine provided with an intermittent driving-gear for the fabric to be printed, comprising a drum, over which passes the fabric-carrying aprons, a star-wheel revolving with the drum and having radial slots, and a shaft having oppositely-disposed arms, friction-rollers on the arms and adapted to pass alternately into the said slots to intermittently rotate the drum, the said friction-rollers being disposed diametrically opposite each other and equidistant from the axis of 90 the shaft.

3. An oil-cloth-printing machine provided with a printing-block-supporting frame comprising a support for the printing-block, side arms for the said support to rest on, and means 100 for adjusting the said support lengthwise and transversely on the said side arms.

4. An oil-cloth-printing machine provided with a printing-block-supporting frame, comprising spaced beams, arms secured to the ends 105 of the beams, side arms having heads for the beam-arms to rest on, and means for adjusting the said beam-arms transversely and longitudinally on the said side-arm heads.

5. An oil-cloth-printing machine provided 110 with a printing-block-supporting frame comprising a support for the printing-block, side arms for the said support to rest on, means for adjusting the said support lengthwise and transversely on the said side arms, a printing-block, and means for adjustably attaching the printing-block to the said support.

6. An oil-cloth-printing machine provided with a printing-block having spaced plates, supporting-beams, clamping-bars for removably securing the said plates to the flanges of the said supporting - beams, and adjusting-screws on the said plates, abutting the edges of the beam-flanges. 120

7. An oil-cloth-printing machine provided 125 with a printing-block-supporting frame comprising spaced supporting - beams, arms attached to the ends of the said beams, side arms having heads for the said beam-arms to rest on, bolts screwing in the said heads and ex- 130

tending through enlarged openings in the said beam-arms, means for shifting the said supporting - beams and their arms transversely, and means for shifting the said beams and their arms longitudinally.

8. An oil-cloth-printing machine provided with a printing-block-supporting frame comprising spaced supporting - beams, arms attached to the ends of the said beams, side arms having heads for the said beam-arms to rest on, bolts screwing in the said heads and extending through enlarged openings in the said beam-arms, adjusting-blocks held longi-

tudinally adjustable on the said heads and provided with pins engaging elongated slots in the said beam-arms, and set-screws screwing on the said heads, against the said adjusting-blocks.

In testimony whereof I have signed my name to this specification in the presence of two sub- 20 scribing witnesses.

WILLIAM HUBELI WALDRON.
